[57] CLAIM

The ornamental design for a survival gun stock, substantially as shown and described.

DESCRIPTION

FIG. 1 is a right side elevational view of a one-piece right-hand model of my survival gun stock design;

FIG. 2 is a top plan view thereof;

FIG. 3 is a left-side elevational view thereof;

FIG. 4 is a bottom plan view thereof;

FIG. 5 is a rear elevational view thereof;

FIG. 6 is a front elevational view thereof;

FIG. 7 is a left side elevational view of a second embodiment of the design shown in FIG. 1 and showing a one-piece left-hand model of my survival gun stock design;

FIG. 8 is a top plan view of FIG. 7;

FIG. 9 is a right side elevational view of FIG. 7;

FIG. 10 is a bottom plan view of FIG. 7;

FIG. 11 is a rear elevational view of FIG. 7;

FIG. 12 is a front elevational view of FIG. 7

FIG. 13 is a right side elevational view of a third embodiment of the design shown in FIG. 1 and showing a two-piece right-hand model of my survival gun stock design;

FIG. 14 is a top plan view of FIG. 13;

FIG. 15 is a left side elevational view of FIG. 13;

FIG. 16 is a bottom plan view of FIG. 13;

FIG. 17 is a rear elevational view of FIG. 13;

FIG. 18 is a front elevational view of FIG. 13;

FIG. 19 is a left side elevational view of a fourth embodiment of the design shown in FIG. 1 and showing a two-piece left-hand model of my survival gun stock design;

FIG. 20 is a top plan view of FIG. 19;

FIG. 21 is a right side elevational view of FIG. 19;

FIG. 22 is a bottom plan view of FIG. 19;

FIG. 23 is a rear elevational view of FIG. 19; and

FIG. 24 is a front elevational view of FIG. 19.
